Primary Examiner—Martie K. Holtje*Attorney, Agent, or Firm*—Albert O. Cota**[57] CLAIM**

The ornamental design for a transparent notebook insert having a plurality of overlapping transparent flaps having side pockets, as shown and described.

DESCRIPTION

FIG. 1 is a front elevational view of a transparent notebook insert having a plurality of overlapping transparent flaps having side pockets showing my new design;

FIG. 2 is a rear elevational view thereof;

FIG. 3 is a top plan view thereof;

FIG. 4 is a bottom plan view thereof;

FIG. 5 is a left elevational view thereof;

FIG. 6 is a right elevational view thereof; and,

FIG. 7 is a front elevational view of a second embodiment illustrating a transparent notebook insert having a plurality of longitudinal, overlapping transparent flaps having on each side a pocket.
